UNITED STATES PATENT OFFICE

2,531,944

TEXTILE MACHINE

Arthur G. B. Metcalf, Milton, Mass.

Application February 4, 1946, Serial No. 645,410

11 Claims. (Cl. 28—51)

1
The present invention relates in general to textile and similar thread-handling machines, and in particular to the combination with such machines of electrical apparatus for detecting the breakage of a thread.

Heretofore, it has been known to provide travelling threads, filaments, and the like, as for example the threads of warping frames or creels in textile machines, with so-called drop wires or equivalent contactor devices which stop the machine or give an alarm signal by completing an electrical circuit upon the breakage of a thread. Such arrangements are complicated, dangerous, and uncertain in operation due to the fact that the currents involved are usually large, so that the closing of a circuit by a drop wire contactor causes considerable sparking, which, with the lint and dust normally present in the atmosphere around the machine, creates an ever-present hazard of fire and dust explosion. Furthermore the contacts frequently become fouled resulting in failure of the device and the machine may continue to function even though a thread may have been broken.

In the present invention, it is proposed to provide an electronic relay-amplifier between the contactor device and the alarm or motor stop mechanism, so that an extremely minute current is sufficient to effect operation, thus greatly reducing the hazard of fire or explosion, and providing reliable filament-break detection and stop motion even upon poor contact of the drop wire contactor.

It is accordingly an object of this invention to provide in a machine for weaving, spinning, or the like, a filament-break detection apparatus which operates positively and reliably under any conditions in which it may normally be used.

It is another object of this invention to provide such filament-break detection apparatus which requires only a very minute current to effect operation, thereby minimizing the dangers of fire and explosion.

It is a further object of this invention to provide such apparatus for simultaneously indicating the breakage of a filament, and shutting down the machine.

It is a still further object of this invention to provide thread-break detection apparatus of the type described for a loom or the like having more than one bank of travelling threads which will permit ready identification of the bank in which a broken thread exists.

It is still another object of this invention to provide such thread break detecting apparatus in

2
a multi-bank loom or the like which will permit ready identification of the bank in which a broken thread exists and simultaneously interrupt the operation of the loom.

5 Other objects and features of the present invention will become apparent from the following description. The description refers to the drawings in which:

Fig. 1 illustrates partly in electrical scheme and partly in perspective the essential elements of the invention;

Fig. 2 illustrates the invention as applied to a loom having three banks of warp-forming threads;

15 Fig. 3 illustrates the invention as adapted to provide an indication of the bank in which a broken thread exists in the loom of Fig. 2;

Fig. 4 illustrates the invention as further adapted to provide simultaneously an indication 20 of the bank in which the broken thread exists and interruption of the motor power to the loom;

25 Figs. 5 and 6 illustrate other types of circuit completing devices that may be used in place of the drop contactors illustrated in Fig. 1.

While it will readily be apparent that this invention will provide improved filament-break detection for any filament-handling machine, the description is directed only to the application of the invention to a textile machine as a convenient illustration. Accordingly, in Fig. 1, thread-break detection apparatus 15 as commonly found in a loom is shown enclosed in a dotted line box and comprises first and second bars of conductive material, 10 and 11 respectively, substantially parallel and separated from each other by suitable insulating material 12. The bars run across the loom beneath threads 14, and conductive drop contactors 13, made of a suitable material, such as copper, are supported each upon an individual thread. The contactors 13 are each in constant slideable contact with the first bar 10 and are supported above the second bar 11 so that when a supporting thread 14 breaks, the associated contactor 13 will fall and establish electrical contact

30 between the bars 10 and 11.

35 As hereinabove stated, it has hitherto been customary to employ the drop contactors 13 as switches in a circuit having relatively high current and thereby to close the circuit to operate a relay or other operator device. In accordance with the present invention, an electronic relay 16, shown enclosed in a dotted line box, which may be of any suitable type, as for example that disclosed in Patent No. 2,357,371, to William F. Wolfer, II, dated September 5, 1944, is interposed be-

40

45

50

55

tween the detecting apparatus 15 and the operator means, which may comprise a magnetic relay 29 controlling a contact 35, so that a relatively small current controlled by the contactors 13 will effect operation of the operator means, 5 through the electronic relay. The electronic relay apparatus 16 comprises generally an electronic discharge device or tube 20 having at least an anode 21, a cathode 22 and a control grid 23. The electron tube 20 is supplied with alternating 10 potential at terminals 25 and 26. Bar 10 may be connected to terminal 26 or both bar and terminal may be grounded as shown. The energizing coil 30 of the relay 29 is connected in the anode, cathode circuit of tube 20. The second bar 11 is connected to the grid 23 through the grid terminal 28. As long as an open circuit exists between 15 terminals 28 and 26, condenser 81 is charged by grid current flowing during the half cycles when terminal 25 is positive and the charge provides a sufficient negative grid bias to maintain tube 20 non-conductive during the half cycles when terminal 26 is positive. Relay 29 is, therefore, de-energized. When terminal 28 is connected to 20 terminal 26, or the resistance between the terminal is substantially reduced, as by the dropping of a contact member 13 due to thread breakage, the current through resistance 82 is substantially increased, and the potential drop across the resistance, during the half cycles when terminal 26 is positive, overcomes the bias applied by condenser 81 and renders the tube conductive. Relay 29 is then energized and closes contact 35. It is thus apparent that, upon breakage of a 25 thread 14, the associated drop contactor 13 closes a circuit between the input terminals 26 and 28, and effects operation of the electronic relay 16, and therefore of the relay 29 and the switch 35. This switch 35 may control alarm or motor 30 circuits involving relatively great current and power, examples of which are hereinafter set forth in detail.

Referring now to Fig. 2, there is illustrated in part a loom having vertical supporting columns 40 and 41 and a plurality of contactor devices 15, each including the elongated conductive bars 10 and 11. Groups of threads 14, which may be warp-forming threads, are arranged in banks, of which only one is here illustrated, and supported between the vertical columns 40 and 41 by horizontal runners 42. A pair of conductor bars 10 and 11 is arranged beneath each bank of threads 14 and upon each thread is suspended a drop contactor 13, as illustrated in greater detail in Fig. 1. Each first bar 10 is grounded and the second bars 11 are all connected in parallel to the grid input terminal 28 of an electronic relay 16, again as shown in Fig. 1. The second bars 11 may be connected together in parallel as shown, or in series if desired, there being no difference in the result of either of these connections, since the drop contactors 13 all cause switching action in parallel, and if any one of them drops, a switching action will take place and cause the electronic relay 16 to become operative. To the output terminals 44 and 45 of the switch 35 there is connected an alarm 46, which may have any desired characteristics, so that upon the dropping of any drop contactor 13 a circuit is closed causing operation of the alarm 46 through the relay 16 and switch 35. A particular type of alarm that is suitable for use with a loom is discussed hereinafter in connection with Fig. 4.

Fig. 3 illustrates another arrangement of elec-

tronic relays 16 and alarms 46 which may be adopted to provide a signal that will enable one not only to stop the loom, but also to identify the bank in which the broken thread exists. The left hand half of the loom of Fig. 2 is shown in part, including one vertical supporting column 40 and the appropriate ends of the three sets of contactor bars 10 and 11. As heretofore, the first conductive bar 10 is grounded. However, each second conductive bar 11 is connected to the input grid terminal 28 of an individual associated electronic relay 16, the relays being distinguished by Roman numerals I, II and III. The negative terminal 25 of each electronic relay is grounded, so that the signal input circuit for each electronic relay is the same as in Fig. 1. A separate alarm 46 I, II or III is operated by each relay. Thus, when a thread breaks in any bank, the alarm 46 of that bank will operate, and in addition to giving an alarm, will indicate in which bank the breakage occurred.

To illustrate how the invention may be adapted to indicate the bank in which a thread breakage occurs and simultaneously automatically stop the loom, reference is made to Fig. 4. There in dotted line boxes is enclosed the apparatus of three identical suitable alarms 46¹ which are adapted to accomplish these purposes. The alarms 46¹ are distinguished by Roman numerals I, II and III in accordance with the plan of Fig. 3. In each alarm 46¹ there is included a normally closed switching relay 50 and a lamp 51. The normally closed relays 50 are all arranged so that their switches 52 are in series with the power to a motor M, which may provide the driving power for the loom. Power is brought to the motor M through appropriate input terminals 54 and 55 and wires 58 and 59, and to these terminals there are also connected in parallel two wires 56 and 57 to carry power for energizing the relays 50 in the alarms 46¹. In series connection with each relay 50 is the switch 35 of the associated electronic relay 16, I, II or III (illustrated in Fig. 3), and a lamp 51. The alarms 46¹ are all connected in parallel to the power input terminals 54 and 55.

When a switch 35 closes, the relay 50 of the associated alarm 46¹ will operate and open its switch 52, thus interrupting power to the motor M and shutting down the loom. Simultaneously, the power for the relay 50 will flow through the associated lamp 51, and the lamp will light and indicate that the thread bank with which the particular alarm 46¹ and switch 35 are associated has in it a broken thread. A current return path is provided for each alarm 46¹ to the terminal 54 through a direct wire 56. An alternative return path may be had to terminal 54 through the unlighted lamps 51 and non-energized relays 50 of the remaining alarms 46¹. However, this alternative return path offers a relatively large impedance to the flow of electrical current, and therefore the major portion of return current will flow through the direct wire 56, and the remaining lamps 51 will not be lighted nor will the other relays 50 be operated. Thus the apparatus of Fig. 3 may be adapted simultaneously to shut off the loom and indicate the bank in which a thread-breakage exists, whenever the breakage of a thread 14 occurs.

As hereinabove stated, relay apparatus 16 of the electronic type is adapted to become operative not only when a positive connection is made between the grid terminal 28 and terminal 26, 75 but also when the resistance between terminals

28 and 26 is substantially reduced. Accordingly, other switching apparatus than the elongated conduct 10 and 11 and drop contactors 13 may be used, such as for example capacitive switching apparatus as illustrated in Fig. 5, or inductive switching apparatus as illustrated in Fig. 6.

The apparatus of Fig. 5 comprises an elongated fixed condenser plate 60, and a plurality of movable smaller condenser plates 61. As illustrated in cross section, holes 63 are provided in each movable plate 61 for guiding the plate upon vertical poles 62 mounted on the fixed plate 60. The poles 62 may be of any suitable insulating material such as hard rubber or polystyrene. The movable plates 61 are adapted to fall toward the fixed plate 60, and to come to rest on the enlarged base portions 64 of the poles 62. A hook 65 is provided on each movable plate 61 for attachment to a thread 14 in substantially the same manner as the drop contactors 13 are so attached in Fig. 1. Flexible partly coiled wires 66 furnish conductive contact between the movable plates 61 and a bus bar 67 which is further connected to a terminal 68. This last-mentioned terminal 68 is adapted to be connected to the input grid terminal 28 of the electronic relay apparatus 16 or similar apparatus. The fixed condenser plate 60 is grounded, or may be connected to the second input terminal 26.

When the hooks 65 are attached each to a thread (not shown), the movable plates 61 are each held a predetermined distance away from the fixed plate 60. However, when a thread breaks, the associated movable condenser plate 61 falls until it comes to rest on the base portions 64 of the guiding poles 62, thus decreasing the distance between the two condenser plates 60 and 61. This decrease in distance will effect a reduction in the capacitive reactance of the apparatus, and likewise in the impedance of the input circuit of an electronic relay 16 to which it may be connected, thus having an effect of the same nature as the dropping of a conductive contactor 13 to Fig. 1 and causing operation of the electronic relay apparatus in the same manner as discussed above. It is to be noted that there is no conductive contact between the plates 60 and 61 and hence no possibility of sparking between those plates, and thus the hazard of fires and explosion caused by sparking in the presence of lint, is completely eliminated in this apparatus.

The switching mechanism of Fig. 6 which is illustrated mainly in electrical scheme, comprises a transformer 70 having a primary winding 71 and a short-circuited secondary winding 72. The primary 71 has one end grounded and the other end connected to a terminal 18 which, like the terminal 68 of the apparatus of Fig. 5 is adapted to be connected to the grid input terminal 28 of the electronic relay apparatus 16. A thread-engaging hook 73 is provided on the short-circuited secondary 72 and has the same purpose as the hook 65 of the capacitor switching apparatus in Fig. 5. The short-circuited secondary 72 is adapted to rotate about a point 74 as an axis and is normally maintained in the vertical position illustrated in Fig. 6 when the hook 73 is resting on a thread (not shown). The weight of the secondary is preferably so distributed about the point 74 that it will tend to fall to a disposition in which it is substantially parallel to the primary 71 when not otherwise constrained.

When alternating current flows in the primary

winding 71 and when the secondary winding 72 is disposed substantially perpendicularly thereto, a relatively high impedance is offered to the flow of current in the primary winding. However, when the short-circuited secondary 72 is substantially parallel to the primary 71, the primary then has a relatively low impedance, and a relatively large current may be permitted to pass. Thus, upon the breakage of a supporting thread (not shown) with which the hook 73 may have been engaged, the short-circuited secondary 72 will fall and permit the passage of a larger current through the primary 71 by lowering its inductive reactance. Like the capacitive switch of Fig. 5, the apparatus of Fig. 6 is adapted to lower the impedance of the input circuit of electronic relay apparatus 16 when properly connected thereto. This apparatus also will permit spark-free thread-break detection.

Obviously various changes may be made in the above-described articles and different embodiments of the invention can be made without departing from the scope thereof. It is therefore intended that all matter contained in the above description or shown in the accompanying drawings shall be interpreted as illustrative only, and not in a limiting sense, and that the invention is to be limited only by the prior art and the spirit of the appended claims.

30 What is claimed is:

1. For machines for the weaving, spinning and the like of filamentary material, filament-break detecting means comprising: an electron discharge device having an anode, cathode, and control electrode; an output circuit including said anode and cathode; and an input circuit including said cathode and control electrode; a plurality of electrical reactance controlling means arranged in mutually parallel connection in said input circuit and each supported by an individual filament in a predetermined disposition but adapted upon breakage of the supporting filament to assume and maintain a new disposition and thereby alter the electrical character of said input circuit; and operator means adapted to be energized by said output circuit.

2. In combination with a machine for operating upon a filament, means for detecting the breakage of said filament comprising: an electron discharge device having an anode, cathode and control electrode; an output circuit including said anode and cathode; a variable capacitance comprising, a movable member supported by said filament, and a fixed member; an input circuit including said cathode, control electrode, and capacitance, and adapted to render and maintain said discharge device conductive upon the breakage of said filament; and operator means adapted to be energized by said output circuit.

3. In combination with a machine for operating upon a filament, means for detecting the breakage of said filament comprising: an electron discharge device having an anode, cathode and control electrode; an output circuit including said anode and cathode; a variable inductance having a movable member the position of which is altered upon breakage of said filament; an input circuit including said filament; an input circuit including said cathode, control electrode and inductance, and adapted to render and maintain said discharge device conductive upon the breakage of said filament and operator means adapted to be energized by said output circuit.

4. A thread break detection device comprising: an electron discharge device having an anode,

cathode, and control electrode; an output circuit including said anode, said cathode; a detecting impedance comprising a conductive channel, having an insulating channel mounted therein, a bar mounted in said insulating channel, and a hollow rectangular member of conductive material in slidable contact with said conductive channel, and adapted to be suspended on a thread and upon breakage of the thread to drop into contact with said bar; an input circuit including said cathode, a device for storing electrical energy, and said detecting impedance, and adapted to render and maintain said discharge device conductive upon thread breakage; and operator means adapted to be energized by said output circuit.

5. A thread break detection device comprising: an electron discharge device having an anode, cathode, and control electrode; an output circuit including said anode, said cathode; a variable capacitance comprising a movable member adapted to be supported by a thread, and a fixed member; an input circuit including said cathode, control electrode, and capacitance, and adapted to render and maintain said discharge device conductive upon thread breakage; and operator means adapted to be energized by said output circuit.

6. A device according to claim 5 in which said capacitance comprises a pair of parallel plates maintained in alignment by insulating studs.

7. A thread break detection device comprising: an electron discharge device having an anode, cathode, and control electrode; an output circuit including said anode, said cathode; a variable inductance having a movable member, the position of which is altered on thread breakage; an input circuit including said cathode, control electrode and inductance, and adapted to render and maintain said discharge device conductive upon thread breakage; and operator means adapted to be energized by said output circuit.

8. A device according to claim 7 in which said inductance comprises a fixed inductance coil, and a movable coil rotatable with respect to said fixed coil.

9. For machines for the weaving, spinning and the like of filamentary material, filament-break detecting means comprising; an electron discharge device having an anode, cathode and control electrode; an output circuit including said anode and cathode; an input circuit including said cathode, said control electrode, and a capacitance; a plurality of electrical impedance controlling means arranged in mutually parallel connection in said input circuit and each supported by an individual filament in a predetermined position but adapted upon breakage of the supporting filament to assume and maintain a new disposition and thereby alter the electrical character of said input circuit; operator means adapted to be energized by said output circuit upon breakage of any one of said filaments; and means controlled by said operator means for interrupting a power circuit independent of said output circuit and for providing a thereafter

continuing indication that said breakage has occurred.

10. In combination with a machine for operation upon filaments, means for detecting the breakage of any of said filaments comprising: an electron discharge device having an anode, a cathode and control electrode; an output circuit including said anode and cathode; an input circuit including said cathode, said control electrode, and a capacitance; a plurality of impedance controlling means arranged in mutually parallel connection in said input circuit, each of said controlling means being supported by one of said filaments in a predetermined disposition, but adapted upon breakage of its supporting filament to assume and maintain a new disposition and thereby alter the electrical character of said input circuit; and operator means adapted to be energized by said output circuit, said operator means consisting in means for indicating the breakage of said filament and means for interrupting a power circuit independent of said output circuit, and being adapted upon the breakage of said filament to interrupt said power circuit and simultaneously to provide a thereafter continuing indication that said breakage has occurred.

20 11. In combination with a machine for operating upon filaments, means for detecting the breakage of any of said filaments comprising: an electron discharge device having an anode, cathode and control electrode; an output circuit including said anode and cathode; an input circuit including said cathode, said control electrode, a capacitance and a plurality of parallel connected detecting impedances, and adapted to render and maintain said discharge device conductive upon the breakage of any of said filaments; and operator means adapted to be energized by said output circuit and when energized to interrupt the power supply to said machine and to actuate indicating means.
